UNITED STATES PATENT OFFICE.

REUBEN N. TRANE, OF LA CROSSE, WISCONSIN.

ROTARY PUMP OR MOTOR.

Application filed February 14, 1920. Serial No. 358,707.

To all whom it may concern:

Be it known that I, REUBEN N. TRANE, a citizen of the United States, and a resident of La Crosse, in the county of La Crosse 5 and State of Wisconsin, have invented a new and useful Improvement in Rotary Pumps or Motors, of which the following is a full, clear, and exact description.

An object of my invention is to provide a 10 pump which may be used for pumping liquids or gases, which is simple in construction, but in which certain defects that are often found in rotary pumps and motors of this type are eliminated, such as excessive 15 vibration and wear of the apparatus.

A further object of my invention is to provide a rotary pump which, unlike most of the pumps of the type, has, instead of a 20 line contact, surface contact of relatively considerable area, thereby obviating the disadvantages which arise when the contacting surfaces are worn, and which, in devices of the line contact type, cause the pump to leak after the slightest wear on the line 25 of contact.

A further object of my invention is to provide a pump in which the use of an eccentric mass is substantially eliminated, thereby reducing vibration and providing a 30 pumping device having a pumping characteristic which is parallel to the characteristic of the piston pump, and has, moreover, greater efficiency.

Other objects and advantages will appear 35 in the following specification, and the novel features of the invention will be particularly pointed out in the appended claim.

My invention is illustrated in the accompanying drawings, forming part of this 40 application, in which—

Figure 1 is a side view of the pump, the cover plate being removed,

Figure 2 is a section along the line 2—2 of Figure 1, the cover plate being in position,

Figure 3 is a view similar to Figure 1, showing the piston in a different position,

Figure 4 is a view similar to Figure 1, showing the piston in another position,

Figure 5 is a perspective view of the rotor,

Figure 6 is a top view of a piston, and

Figure 7 is a face view of the piston.

In carrying out my invention, I provide a 55 base portion 1 which supports an integral casing 2 of the shape shown in the drawings.

The casing has an integral bearing portion 3 for a shaft 4 of a rotor 5. An inlet 6 and an outlet 7 are provided on opposite sides of the casing, these portions being 60 preferably threaded, as shown at 6^a and 7^a for convenient attachment to pipes (not shown).

The casing 2, it will be seen, has on the interior thereof a bearing surface 8 (see 65 Figure 2) against which the rotor 5 bears. Adjacent the inlet and the outlet pipes the casing is cut away to provide spaces 9 and 10. The sides of the casing are also cut away along the side of the rotor, as shown at 70 11 and 12 respectively, to reduce the frictional contact of the rotor with the bearing surface 8.

The rotor 5 is provided with a cylindrical bore 13 extending from one side to the other, 75 the axis of the bore 13 passing through the center of the rotor. The rotor also has an opening 14 extending at right angles to the bore 13 and communicating therewith at its central portion.

In Figure 7 I have shown a piston 15 which is cylindrical in shape, the ends 15^a and 15^b being carved to conform with the curvature of the rotor, so that when the piston is at either end of the bore 13, it will 85 form a continuation of the surface of the rotor. The piston is provided with a cylindrical recess 16 extending inwardly from one side. It will be noted that this recess is toward one end, i. e., the end 15^a. Disposed within the recess is a cylindrical bushing 17 which is provided with an opening 18 disposed eccentrically thereof and arranged to receive a stub shaft 19 carried by a cover plate 20 (see Figure 2).

From the foregoing description of the various parts of the device, the operation thereof may be readily understood. Figure 2 shows the device as assembled. The shaft 4 and the shaft 19 are parallel. The opening 18 in the bushing 17 is disposed eccentrically with respect to the bushing, the bushing 16 being free to turn on the shaft 19 which is rigidly secured to the cover plate 20, the latter being secured to the casing by 105 means of bolts 21.

Consider Figure 1. In this position the piston 15 has its upper edge 15^a in contact with the interior wall of the casing. The lower edge is spaced from the casing. The 110 space 9 which communicates with the inlet, as well as the space 10, is, in the position

shown in Figure 1, shut off from communication with the space between the end of the piston 15^b and the lower inner wall of the casing. If, now, there is a movement of the rotor in a clockwise direction, there will be a movement of the piston, due to the eccentricity of the opening 18, from the position shown in Figure 1 to that shown in Figure 3 when the rotor has moved 90°.

10 On further revolution of the rotor, the piston will take the position shown in Figure 4.

Consider now Figure 3. As the rotor moves, the space adjacent to the end 15^a will tend to grow larger, while the space adjacent to the end 15^b will tend to grow smaller. The water or other fluid flows into the space, is trapped in the manner shown in Figure 4 and is forced out on the other side through the outlet 7, due to the reciprocation of the piston as the rotor is turned. It will be observed that the water cannot return to the inlet at the top, because the piston is then bearing against the upper inner wall of the casing, nor can it return on the lower side, because the wall of the rotor will prevent it. There is thus a pumping action which is imparted by the reciprocating piston. It will be observed that this form of the device is a great improvement over those rotary pumps in which the contact is a line contact and in which the slightest wear on the line contact will cause the pump to leak. The device has the advantages of a rotary

pump and also the advantages of a reciprocating pump.

Obviously, the device could be used as a motor, since, when pressure is applied to the piston, it would tend to rotate the rotor. While I have shown a cylindrical piston, it is obvious that the shape may be varied and that it might be fitted with piston rings or packing without departing from the spirit and the scope of the invention.

I claim:

In a rotary pump or motor, a casing provided with an inlet on one side and an outlet on the opposite side, a cylindrical rotor disposed within the casing and being arranged to engage certain portions of the walls thereof between the inlet and the outlet, said rotor having a bore extending therethrough and a recess extending at right angles to said bore, a piston disposed in said bore and having a recess registering with the recess in said rotor, the ends of the piston being curved to conform with the contacting surface of the rotor, and means for causing the reciprocation of the piston to trap the fluid from the inlet and to force it through the outlet, said means comprising a stationary member carried by the casing and extending into the recess in said piston, and a rotatable member eccentrically mounted on said stationary member within said recess and arranged to engage the walls of the recess in said piston.

REUBEN N. TRANE.
